LAMP HOLDER FOR DOUBLE-ENDED
DISCHARGE LAMPS

Benjamin C. Webster, Fairfield, Conn., assignor
to The Bryant Electric Company, Bridgeport,
Conn., a corporation of Connecticut.

Application March 15, 1945, Serial No. 582,858.

5 Claims. (Cl. 173—328)

1

My invention relates, generally, to lamp holders and, more particularly, to lamp holders of the locking type for use with double-ended electric discharge lamps for preventing the lamp from becoming accidentally disengaged from the holder.

The object of my invention, generally stated, is to provide a lamp holder of the lamp-locking type which is of simple and economical construction and which shall function to prevent a lamp from becoming accidentally disengaged from the holder for any reason.

A more specific object of my invention is to provide a lamp holder of the character described wherein an L-shaped lever member is mounted upon the housing portion of the holder for rotational movement into and out of a lamp-locking position.

A further object of my invention is to provide a lamp holder of the character described wherein the L-shaped lever member is mounted for rotational movement on the longitudinal axis of the housing portion of the holder between the ends thereof.

Another object of my invention is to provide a lamp holder of the character described wherein the lever member is normally biased to a locking position and movable to unlocking position against the force of the biasing means.

A still further object of my invention is to provide a lamp holder of the character described wherein the L-shaped lever member is rotatably mounted upon a stud extending through the housing portion of the holder and also carrying a biasing spring for normally retaining the lever member in a locking position.

These and other objects of my invention will become more apparent from the following detailed description when considered in connection with the drawing, wherein:

Figure 1 is a front view, in elevation, of a lamp holder embodying the principal features of my invention;

Fig. 2 is a side view, in elevation and partly in section, of the holder of Fig. 1 showing the lever member in its locking position with respect to the lamp;

Fig. 3 is a rear view in elevation of the holder of Fig. 1 wherein the lever member is shown in both its locking and unlocking positions;

Fig. 4 is a side view in elevation of the lever member;

Fig. 5 is a front view in elevation of the lever member;

Fig. 6 is an end view of the lever member;

Figs. 7 and 8 are side and end views, respective-

ly, of the stud member on which the lever member is mounted and

Figs. 9 and 10 are side and end views, respectively, of the biasing spring.

Referring now to the drawing and, particularly, to Figs. 1, 2, and 3, there is shown a lamp holder of the lamp-locking type constructed in accordance with a preferred embodiment of my invention. The holder comprises, generally, a housing member 10, a pair of contact fingers 11 and 12, mounted therein and a lever member 13.

The housing may be of the shell type having a base portion 14 and a recess 15, as shown in Fig. 2, for receiving the contact fingers 11 and 12. The recess 15 is covered by a back plate 16 shown in Fig. 3.

The contact fingers 11 and 12 may be mounted within the housing in any suitable manner and have their free ends disposed in the recess 15 in cooperative relation with a slot 17 formed in the face of the housing, as shown best in Fig. 1. The slot 17 has an entrance portion 18 through which the contact pins 19 of the lamp 20 are inserted, one after the other, when the lamp is being mounted in the holder. The slot 17 also has a straight portion 21 and a circular portion 22 through which the lamp pins 19 move when the lamp is rotated into contact-making position with the fingers 11 and 12. As shown in Fig. 1, the lamp 20 is in its normal position with its contact pins 19 engaging the contact fingers.

In this embodiment of the invention, the lever member 13 constitutes the lamp-locking element of the holder. The lever member 13 is preferably formed of flat spring material, as shown best in Figs. 4 and 5, and comprises a flat shank portion 23 and a bent-over end portion 24. The shank portion 22 is provided with an opening 25 adjacent its free end which is utilized to mount the lever member upon the housing.

The lever member 13 may be attached to the housing 10 in any suitable manner, such as by means of a stud member 26 riveted therein as shown at 26a. The housing is provided with an opening 27 intermediate its ends for receiving the stud member 26. The opening 27 extends from the front to the back of the housing, and its back portion is enlarged, as indicated at 28. As shown best in Fig. 2, the lever member 13 is positioned with its flat shank portion 23 against the back of the housing, and the bent-over portion 24 extends forwardly toward the face of the housing so as to beneath or over the base of the lamp when in a locking position, as shown in Fig. 2.

In this instance, provision is made for normally

biasing the lever member 13 to its locking position. This is effected by means of a coil spring 30 mounted within the enlarged portion 28 of the opening 27 about the stud member 26, as shown in Fig. 2. In order to limit the movements of the lever member, the rim of the housing is cut away at 32 to provide stops 33 and 34, as shown in Fig. 3. The stop 33 limits the movement of the lever member 13 out of the locking position, and stop 34 determines the position of the lever member when it is biased to its locking position.

As shown in Figs. 4 and 5, the bent-over portion 24 of the lever member is provided with integral finger tabs 35 for the purpose of actuating it to its locking and unlocking positions.

It will be apparent when the locking lever 13 is in its locking position, as shown in Fig. 2, for example, the lamp 20 cannot become accidentally disengaged from the holder for the reason that the bent-over end portion 24 of the lever extends outwardly past the face of the housing in such position as to overlap with the base of the lamp. The bent-over portion 24 of the lever member may be curved transversely, as shown in Fig. 5, for example, so that when the lever is in locking position, the bent-over end portion engages or is closely adjacent to the base of the lamp.

In view of the foregoing, it will be understood that by means of this arrangement, the lamp is securely and positively locked within the holder, and that it may be readily removed by simply actuating the lever member 13 from the locking position against the force of the biasing spring 30. It will be understood further that the biasing spring functions to at all times maintain the lever member in its locking position, and that it is impossible to leave the lever member in an unlocking position when inserting or removing a lamp.

While in this embodiment of the invention, the lever member 13 has been shown as being normally biased to its locking position, it is apparent that this lever member may be utilized as a locking device without the use of the biasing spring. In this instance, the lever member would be retained in its locking position due to the engagement of its bent-over portion with the base of the lamp.

In view of the foregoing description of a preferred embodiment of my invention, it will be apparent that I have provided a lamp holder of the locking type which shall effectively function to lock the lamp within the holder and which may be readily actuated to permit the removal of the lamp therefrom.

While I have disclosed a particular embodiment of my invention, it will be apparent that changes and modifications may be made therein without departing from the principles of the invention.

I claim as my invention:

1. A lamp holder for use with double-ended discharge lamps having a plurality of contact pins at each end comprising, a housing having a slot in one end thereof to receive the contact pins of the lamp, a plurality of contact fingers mounted therein in cooperative relation with the slot, an L-shaped lever member rotatably mounted upon the back face of the housing for movement in a plane substantially parallel to said back face of the housing to and from a locking position, said housing having stop means disposed to stop said lever member in its locking position, said lever member having a bent-over end portion extending over the slotted end of the housing, and

spring means normally biasing said lever member to its locking position.

2. A lamp holder for use with double-ended discharge lamps having a plurality of contact pins at each end comprising, a housing having a slot in one end thereof to receive the contact pins of the lamp, said housing having a shallow recess in the back face thereof a plurality of contact fingers mounted therein in cooperative relation with the slot, and an L-shaped lever member rotatably mounted upon the back face of the housing on the longitudinal axis thereof for limited movement in said shallow recess between locking and unlocking positions with respect to the slotted end of the housing, said lever member having a flat shank portion and a bent-over end portion extending in the direction of the front face of the housing, and spring means mounted within the housing normally biasing the lever member to its locking position.

3. A lamp holder for use with double-ended discharge lamps having a plurality of contact pins at each end comprising, a housing having a slot in one end thereof to receive the contact pins of the lamp and a stop member on one face thereof, a plurality of contact fingers mounted therein in cooperative relation with the slot, said housing having an opening therethrough from front to back face on the longitudinal axis thereof, a stud member mounted in said opening, an L-shaped lever member mounted upon said stud member for rotational movement into and out of a locking relation with respect to the slotted end of the housing, said lever member being disposed to engage said stop member in its locking position, and a coil spring mounted on said stud member normally biasing the lever member to its locking position.

4. A lamp holder for use with double-ended discharge lamps having a plurality of contact pins at each end comprising, a housing having a slot in one end thereof to receive the contact pins of the lamp and spaced stop portions on the back face thereof, a plurality of contact fingers mounted therein in cooperative relation with the slot, said housing having an opening therethrough from front to back face intermediate its ends, a headed stud member mounted in said opening with its head portion at the back face of the housing, an L-shaped lever member rotatably mounted upon said stud for movement along the back face of the housing between locking and unlocking positions as defined by said stop portions, said lever member having a bent-over end portion extending over the slotted end of the housing, and a coil spring mounted on the stud member within the housing normally biasing the lever member to the locking position with the bent-over end portion thereof positioned adjacent the slotted end of the housing.

5. A lamp holder for use with double-ended discharge lamps having contact pins at each end comprising, a housing having a slot in one end thereof to receive the contact pins of the lamp, a plurality of contact fingers mounted within the housing in cooperative relation with the slot, said housing having an opening therethrough from front to back face intermediate its ends, a stud member mounted in said opening, and an L-shaped lever member rotatably mounted on the stud member on the back face of the housing, said lever member having a shank portion extending along the back face of the housing and a bent over end portion which obstructs the end slot in

the housing when moved thereover, said housing having a shoulder portion on the back face positioned to be engaged by the shank portion of the lever member when it is actuated into such position that the bent over end portion obstructs the end slot.
